UNITED STATES PATENT OFFICE.

CHARLES M. WAITE AND CHARLES F. FRALICK, OF NEW YORK, N. Y.

CLEAT AND SOCKET.

No. 811,186.

Specification of Letters Patent.

Patented Jan. 30, 1906.

Application filed April 14, 1905. Serial No. 255,607.

To all whom it may concern:

Be it known that we, CHARLES M. WAITE and CHARLES F. FRALICK, citizens of the United States, and residents of the borough 5 of Manhattan, in the city of New York, in the county of New York and State of New York, have jointly invented certain new and useful Improvements in Cleats and Sockets, of which the following is a specification.

10 This invention relates to devices for supporting electrical conductors, which devices are at the same time provided with a socket for an electric incandescent lamp.

It is the object of the present invention to 15 provide a combination cleat and socket which may be used in the open air, for which purpose it is necessary that the socket shall be weatherproof, so as to withstand the deteriorating effect of exposure out of doors.

20 The purpose of this invention is carried out by constructing a cleat with a weather- proof socket and so arranging it in relation to the conductors for the electric current and the translating device giving the light that 25 practically no metallic parts whatsoever are exposed.

With these and other objects in view the present invention consists in the combination and arrangement of parts, as will be 30 hereinafter more fully described, shown in the accompanying drawings, and particularly pointed out in the appended claims, it being understood that changes in the form, proportion, size, and minor details may be 35 made within the scope of the claims without departing from the spirit or sacrificing any of the advantages of the invention.

In the drawings, Figure 1 is a front elevation of the device partially broken away. 40 Fig. 2 is a side elevation. Fig. 3 is a view from above, and Fig. 4 is a view of the device from below.

Similar figures of reference indicate corresponding parts throughout the several views. 45 Referring to Fig. 1 of the drawings, the cleat holding the electric conductors consists of the members 1 and 2, provided with recesses 3 for the conductors, and screw-holes 4 for fastening the cleat to a support. The 50 cleat is made of weatherproof material, such as porcelain, stoneware, composition, or other insulating material. The cleat member 2 is provided with a cup or socket member 5, which is integral with one of the cleat members and is provided on its outer side with screw-threaded portion 6, extending

substantially along its entire length. The cup 5 contains the usual openings for the wires 7 and 8, leading to the two terminals 9 and 10, located within the receptacle and 60 serving to make contact with the two terminals of an incandescent electric lamp 13. The wires 7 and 8 are permanently secured to the socket by means of plaster-of-paris, sulfur, or the like in accordance with the 65 usual practice in wiring devices intended for use in the open air. The screw-terminal of the cup 5, consisting of the metallic threaded socket 9, is held in position and at the same time separated from the cup or socket mem- 70 ber 5 by means of an internally-threaded ring 11, of insulating material. A second ring 12, of similar material, is screwed upon the threaded portion 6 of the socket 5 in the position shown in Fig. 1 and serves to further 75 protect any metallic parts of the socket of the lamp which may be exposed to the air. The wires 7 and 8 are spliced and soldered in the usual way to the feed-wires supply- 80 ing the electric currents, as illustrated in Fig. 80 3. The splicing may be covered with insu- lating-tape, as called for by the rules and regulations of the Board of Electric Under- 85 writers. This combination cleat and socket, which forms the subject-matter of the pres- 90 ent invention, complies entirely to the rules of the authorities just mentioned, is per- fectly weatherproof, simple in construction, and easy of application to its purpose.

What is claimed as new and useful, and de- 90 sired to be secured by Letters Patent of the United States, is—

1. In a device of the character described, the combination with a two-part cleat, of a socket carried by one side of said cleat, terminals arranged in said socket and a pair of weatherproof rings, one of which lies between one of said terminals and the wall of said socket, and the other of which encircles 95 said socket.

2. In a device of the character described, a two-part cleat formed of weatherproof material, the members of said cleat being pro- 100 vided with opposed shallow depressions in their engaging faces for the reception of an electrical conductor, said members being fur- 105 ther provided with aligned openings, means for securing the cleat to a fixed support and simultaneously exerting a clamping pressure upon said electrical conductor, a socket integral with one of the members of the said 110 cleat, terminals to which electrical conductors

may be secured, means for insulating one of the terminals from the walls of the socket, and means secured to the outside of the socket adapted to protect the metallic parts 5 of the socket and the lamp held therein.

3. In a cleat for supporting electrical conductors, a pair of cleat members, a weather-proof socket secured to one of the members, electric conductors leading into the socket, 10 terminals to which the conductors are secured, means for insulating one of the terminals from the walls of the socket, and means secured to the outside of the socket

adapted to protect the metallic parts of the socket and the lamp held therein.

15

In witness whereof we have hereunto set our hands, in the presence of two subscribing witnesses, at New York, in the county of New York and State of New York, this 30th day of January, 1905.

CHARLES M. WAITE.
CHARLES F. FRALICK.

In presence of—

RALPH JULIAN SACHERS,
MIMA M. RAMSEY.
